(54) **GAS LIGHT, FROM COTTON SEED**

(76) Inventor: **Denison Olmstead**

Denison Olmsted of New Haven, Connecticut,
Letters Patent,

The schedule referred to in these Letters Patent, and making part of the same, containing a description in the words of the said Denison Olmsted himself of his improvement in the manufacture of gas lights from cotton seed.

To all to whom these presents shall come,

Be it known that I Denison Olmsted of the City of New Haven & State of Connecticut, have invented or discovered a new and useful improvement in the manufacture of gas, to be used for the purpose of illumination, in the form known under the name of gaslights; for which purpose I employ an article or substance which has not heretofore been used for that purpose, for which discovery & improvement I claim a patent according to the laws of the United States.

Whereas I the said Denison Olmsted do hereby declare that the nature of my said discovery & improvement and the manner in which the same may be carried into effect are fully made known in the following description or specification.

The material which I employ & the use of which I claim as my discovery, is the seed of the cotton plant, this after being dried or roasted for the purpose of expelling the watery portion, I put into a retort or other recipient similar to those used for making of gas lights, from coal, tar or other substance in which it is heated to a degree sufficient to convert the oily matter of the seed into vapors, which vapors before it escapes from the recipient into the gasometer is converted into a permanently elastic fluid by being made to pass over an ignited surface either of metal, anthracite, fragments of brick, or other substance, in the way adopted for the

making of gas from oil or other substance.

In the conversion of the only matter of cotton seed into gas I do not specify any particular form of apparatus that is already in use, being sufficient for the purpose, but I do claim as my exclusive right, the employment of cotton seed for the production, by destructive distillation and in a manner adapted to public use, of a permanently elastic & highly illuminating gas; the same being my invention or discovery and not heretofore practised or known.

Witness,

Clad. Bostwick
Anthony Stow, Jr.

Deacon Olmsted
